UNITED STATES PATENT OFFICE.

MICHAEL J. SASGEN, OF CHICAGO, ILLINOIS, ASSIGNOR TO GRAND SPECIALTIES COMPANY, OF CHICAGO, ILLINOIS, A CORPORATION OF ILLINOIS.

DOORSTOP.

Application filed February 23, 1926. Serial No. 89,977.

My invention relates to improvements in door stops of the strut kind. The object of my invention is to provide a stop of this character which shall have a strut which can be readily adjusted as to length; the shoe of which can be readily made from suitable tubing; which shall have an improved form of yielding spring for holding the strut in inoperative position; and which shall be provided with means for interlocking the shoe with the lever in a definite operative position while allowing the adjustment of the shoe on the lever for changing the length of the lever.

Another feature of importance relates to a simple member for interlocking the shoe with the lever or strut and which member is fixed rotatively in relation to the strut, and is provided with lifting lugs always presented at the sides of the lever.

My invention will be more readily understood by reference to the accompanying drawing in which:—

Fig. 1, is a side elevation of a door stop constructed in accordance with my invention;

Fig. 2, is a front elevation of same;

Fig. 3, is a fragmentary, vertical section on the line 3—3 of Fig. 2;

Fig. 4, is a horizontal section on the line 30 4—4 of Fig. 3;

Fig. 5, is a plan view of the locking member in partly formed condition; and

Fig. 6, is a horizontal section on the line 35 6—6 of Fig. 1.

In said drawings 1 represents a door to which the stop of my invention is adapted to be attached, and 2 the floor with which the stop is adapted to contact to hold the door from swinging in one direction.

My improved stop comprises a rigid base member 3 adapted to be secured to the door by screws 4. Near the lower end of the base are a pair of rigid lugs 5 spread apart to receive one end 6 of a swinging strut 7 between them. The strut 7 is pivoted to the lugs 5 to swing up and down by a horizontal pin or pivot member 8 which is secured in perforations in the lugs 5 and passes through a perforation in the end 6 of the strut 7. At the

50 upper end of the base are a second pair of rigid lugs 9 between which the body of the strut 7 is received when it is swung up to vertical position, as shown in dotted lines in Fig. 1. A U-shaped spring 10 is provided

which is received between the lugs 9 and 55 which is formed to clasp the strut and yieldingly hold same in raised, that is, inoperative position. The base member 3 is provided with an opening 11 leading into the space between the lugs 9 to receive the spring 10, and the opening 11 is widened out at the back of the base to receive formed out parts 12 of the spring 10 to prevent the spring moving forward, and the opening is of such depth that when the base 3 is secured to a 60 door the base of the spring contacts the door and the spring is held firmly in place. The prongs 13 of the spring are formed between their ends to clasp the body of the lever. The outer ends 14 of the prongs 13 are bent outwardly and enter notches 15 provided in the outer ends of the lugs 9. The projections 14 overlap the lugs 9 to a slight extent and retain the springs against removal until the device is secured to a door. The forming over 65 of the outer end of the spring to provide the projections 14 provides the prongs with rounded surfaces 16 which permit the rounded body of the strut to enter easily between the prongs.

The outer or free end 17 of the body 7 is cylindrical and is provided with an external screw thread and I provide an improved shoe 18 for cooperation with the body of the strut to form the complete strut. The shoe 85 18 is preferably formed from a piece of tubing, the lower end portion of which is flattened down and bent off at an angle to form a bottom of the shoe, as indicated at 19. The shank 20 of the shoe is left tubular and is internally threaded to fit on the threaded end 17 of the strut body 7. The forming of the bottom of the shoe in the manner described provides a second transverse shoulder 21 in addition to the toe 22 of the shoe and which transverse shoulders help to prevent a rubber envelop 23 from being pushed rearwardly on the shoe when the device is in use. The rubber envelop 23 which covers the lower part of the shoe forms a yielding pad for 90 contact with the floor and is provided with transverse ridges 24 on its bottom surface for assisting in retaining the shoe against slipping on the floor.

The shoe is adjustable on the body of the strut by reason of the threaded engagement and the strut is shortened or lengthened for proper contact with the floor by screwing

the shoe up or down, as the case may be. As the bottom of the shoe is made at an angle to the shank, other than a right angle, there is only one relation of the shoe to the strut 5 which will cause the shoe to properly contact with the floor, consequently in shortening or lengthening the strut the shoe must be rotated one or more complete turns. In order to hold the shoe against being turned 10 after being adjusted, I provide a jam nut 25 of the steeple form for overlapping the thread on the strut and covering same. For locking the shoe to hold it definitely in its right relation with the strut, I provide an 15 interlocking washer 26. This washer is interposed between the top end of the shank of the shoe and the nut 25. It has a central opening 27 which fits freely over the threaded end 17 of the strut member 7 and is formed 20 with two opposite lugs 28 and 29 which project into the opening 27. One of the projections (28) is left as formed and engages in a longitudinal key-way 30 formed in the threaded end 17. The other projection 29 is 25 bent down and engages in a notch 31 provided in the top of the shank of the shoe. It will be readily seen that the interlocking washer 26 cannot rotate on the threaded end 17 by reason of the projection 28 engaging in the 30 key-way 30 and that when the projection 29 enters the notch 31 in the shoe and is held there that the shoe will be held definitely in place.

When it is desired to adjust the length of 35 the strut, the nut 25 is screwed back, the interlocking washer is lifted to free the shoe from the projection 29 and then the shoe is rotated a number of full turns, one or more, as may be necessary. Then to secure the shoe 40 the washer is dropped into place, the projection 29 entering the notch 31 and the nut 25 is screwed hard down. Besides serving to interlock the shoe with the strut the washer 26 has another function. At opposite sides 45 the washer is provided with projections 32 which are arranged to extend out transversely of the strut and provide lugs by which the strut can be readily lifted by the foot of the operator without the necessity of stooping 50 down. To prevent these lifting lugs marring the leather of the shoe in lifting the strut, they are covered preferably by means of a rubber envelop 33, the lugs being enlarged at their outer ends to assist in preventing the 55 envelops being removed. These envelops may either be pre-formed and vulcanized and then pushed on the projections and secured by proper cement, or they may be vulcanized in position. These lifting projections are so 60 related to the inner projections 28 and 29 that when the strut is in operative condition they extend transversely of the strut, or, in other words, parallel with the door 1.

As many modifications of my invention 65 will readily suggest themselves to one skilled

in the art, I do not limit or confine my invention to the specific details of construction herein shown and described.

I claim:

1. In a door stop, a strut member, a base, 70 to which the strut member is pivotally mounted at one end to swing up and down, the strut member comprising a swinging lever and a shoe member mounted on the lever by means of a screw threaded connection, a nut for locking the shoe against rotation, a washer interposed between the nut and the shoe, means for preventing the rotation of the washer on the lever, the washer having a pair of oppositely extending projections 75 at its circumference adapted to extend laterally from the lever to serve as lifting lugs.

2. In a door stop, a strut member, a base, 80 to which the strut member is pivotally mounted at one end to swing up and down, the strut member comprising a swinging lever and a shoe member mounted on the lever by means of a screw threaded connection, a nut for locking the shoe against rotation, a washer interposed between the nut and the shoe, means for preventing the rotation of the washer on the lever, the washer having a pair of oppositely extending projections 85 at its circumference adapted to extend laterally from the lever to serve as lifting lugs, and means for rotationally interlocking the shoe with the washer to retain the shoe in a predetermined rotational relation to the lever.

3. In a door stop of the lever type, a shoe mounted by a screw threaded connection on the free end of the lever for convenience in changing the length of the lever, the shoe having a base arranged at an angle other than a right angle to the lever and adapted to be arranged in a predetermined relative rotational relation for use, a nut for preventing the rotation of the shoe on the lever, a lever lifting member interposed between the shoe and the nut having non-rotatable connection with the lever and means providing non-rotatable engagement between the lifting member and the shoe.

4. In a door stop of the lever type, a shoe 115 for the free end of the lever, the shoe having a tubular shank internally screw threaded to fit on the lever, the opposite part of the shoe presenting a bottom extending at an obtuse angle to the shank and a rubber envelope 120 on said bottom part, means carried by the lever for locking the shoe with its bottom extending in the plane of movement of the lever.

5. In a device of the kind described, a strut 125 lever, a shoe screw-threaded upon the free end of the lever, a nut on the lever above the shoe, a lifting member on the lever between the nut and the shoe, said lifting member having a projection extending into non-ro-

tatable engagement with the lever and a second projection adapted to engage in an opening in the shoe to lock same against rotation.

6. In a door stop of the strut type, a lever 5 pivotally mounted at one end to swing up and down, a shoe adjustably mounted on the free end of the lever, the shoe having a bottom extending at an obtuse angle to the lever, a rubber envelop on the shoe, and bottom of 10 the shoe provided with a transverse shoulder between its ends against which the rubber is pressed when the device operates to hold a door.

7. In a door stop of the strut type, a lever

pivots mounted at one end to swing up and 15 down, a shoe having a bottom extending at an obtuse angle to the lever and having a screw threaded connection with the lever, a nut for clamping the shoe against rotation on the lever, and means interposed between the nut 20 and shoe for causing the shoe to be set with its bottom in proper relation to the door upon which the device is used so that it will properly engage the floor.

In testimony whereof, I have hereunto set my hand, this 16th day of February, 1926.

MICHAEL J. SASGEN.
